UNITED STATES PATENT OFFICE.

WARREN WAGNER, OF STRAWN, TEXAS.

CASING-SPEAR.

1,243,904.

Specification of Letters Patent. Patented Oct. 23, 1917.

Application filed July 21, 1917. Serial No. 182,049.

To all whom it may concern:

Be it known that I, WARREN WAGNER, a citizen of the United States, residing at Strawn, in the county of Palo Pinto and State of Texas, have invented certain new and useful Improvements in Casing-Spears, of which the following is a specification, reference being had to the accompanying drawings.

10 This invention relates to certain improvements in casing spears and it is an object of the invention to provide a novel and improved device of this general character which may be readily and conveniently employed for removing a casing from within a well and which may also be employed for removing a tool which may be dropped within the casing.

15 It is also an object of the invention to provide a novel and improved device of this general character including gripping slips which, when lowered within the casing are held in an inoperative position and wherein a mandrel is employed for releasing the slips 25 when the spear has been lowered a predetermined distance within the casing.

The invention consists in the details of construction and in the combination and arrangement of the several parts of my improved casing spear wherein certain important advantages are attained and the device rendered simpler, less expensive and otherwise more convenient and advantageous for use, as will be hereinafter more fully set 35 forth.

The novel features of my invention will hereinafter be definitely claimed.

In order that my invention may be the better understood I will now proceed to describe the same with reference to the accompanying drawings wherein.

Figure 1 is a longitudinal sectional view illustrating a casing spear constructed in accordance with an embodiment of my invention and in applied position, certain of the slips being shown in an inoperative position; and

Fig. 2 is a longitudinal sectional view of the device as herein embodied, showing certain of the parts in a second position.

As disclosed in the accompanying drawings C denotes a well casing and T a tool therein which is adapted to be removed.

My improved spear as herein disclosed 55 comprises a carrier 1 provided with a longitudinal bore 2 having its outer end portion

3 threaded to afford a convenient engagement therewith by a rope socket or other desired element. The inner end portion 4 of the bore of the carrier 1 is reduced and disposed through said reduced portion 4 is the mandrel 5 which extends within the major portion of the bore 2 and which also extends beyond the inner end of the carrier 1.

60 Detachably engaged with the inner end portion of the carrier 1 is a socket 6 in threaded engagement with the reduced extension 7 arranged at the inner end of the carrier 1. The outer end portion of the socket 6 has its bore reduced as indicated at 8 on a predetermined taper and co-acting with the tapered portion 8 are the slips 9 adapted to engage the tool T or the like to be removed.

75 Resting upon the inner ends of the slips 9 is an annular member or ring 10 snugly fitting within the bore of the socket 6 but capable of movement longitudinally of the bore thereof. The inner end portion of the bore of the socket is intersected by the pin 12 and interposed between the pin 12 and the annular member or ring 10 is the expandable member 14 herein disclosed as a conventional type of coil spring. As is particularly illustrated in Fig. 1 the pin 12 is removable and is adapted to be engaged within the transversely aligned openings 15 spaced apart longitudinally of the socket 6 so that the compression or tension of the expandable member 14 may be regulated in 80 accordance with the necessities of practice. The mandrel 5 also extends within the bore of the socket 6 and in order that the pin 12 will offer no obstruction to the longitudinal movement of the mandrel 5, I provide said mandrel with the slot 16 through which the pin 12 is loosely directed. The slot 16 is of 85 a length in excess of the extent of the inward movement of the mandrel.

90 The carrier 1 at diametrically opposed points is provided with the tapering or inclined seats 17 with which co-act the slips or gripping jaws 18. The slips or jaws 18 are provided with the longitudinally directed slots 19 in which extends the transverse bar or pin 20. The bar or pin 20 is 95 also directed through a second slot 21 produced in the mandrel 5. The slot 21 is also of a length in excess of the extent of inward movement of the mandrel 5. Interposed between the bar or pin 20 and the inner end of the bore 2 proper of the carrier 100

105

110

1 is an expandible member 22 herein disclosed as a coil spring encircling the mandrel 5.

When my improved spear is to be lowered 5 within the casing C the mandrel 5 is forced downwardly and which results in moving the jaws or slips 18 into an inoperative or lowered position as particularly illustrated in Fig. 1 and said mandrel is maintained in 10 such position through the medium of the breakable pin 23 insertible through the openings 24 produced in the carrier 1 and mandrel 5 and adapted to register when the slips or jaws 18 are in inoperative position. 15 When the spear operatively engages with the tool T the mandrel 5 will be moved upwardly or inwardly which results in a severance of the pin 23. Upon the breaking of 20 the pin 23 the expandible member 22 serves to move the pin or bar 24 upwardly resulting in the jaws or slips 18 operatively engaging the casing C as is particularly illustrated in Fig. 2. By this operation it will be at once self evident that upon removing 25 the casing C the tool T will also be withdrawn from within the well.

It will also be understood that by omitting the slips or jaws 18 my improved spear can be employed wholly for the purpose of 30 removing the tool T. It will also be self evident that by reversing my device from the position illustrated in the accompanying drawings the jaws or slips 18 may be employed to remove the casing.

35 From the foregoing description, it is thought to be obvious that a casing spear constructed in accordance with my invention is particularly well adapted for use by reason of the convenience and facility with 40 which it may be assembled and operated and it will also be obvious that my invention is susceptible of some change and modification without materially departing from the principle and spirit thereof and for this 45 reason I do not wish to be understood as limiting myself to the precise arrangement

and formation of the several parts herein shown in carrying out my invention in practice except as hereinafter claimed.

I claim:

1. A casing spear comprising a tubular carrier, a socket engaged therewith, engaging means carried by the socket, gripping jaws slidably engaged with the carrier, a mandrel positioned within the carrier and extending within the socket, said mandrel being provided with a longitudinally disposed slot, a transverse pin engageable with the jaws and loosely directed through the slot of the mandrel, an expandible member 55 constantly urging the pin in one direction, and breakable means co-acting with the carrier and mandrel for maintaining the latter normally against movement under the influence of the expandible member and for 60 normally maintaining the expandible member under compression.

2. A casing spear comprising a tubular carrier, a socket engaged therewith, engaging means carried by the socket, gripping jaws 70 slidably engaged with the carrier, a mandrel positioned within the carrier and extending within the socket, said mandrel being provided with a longitudinally disposed slot, a transverse pin engageable with the jaws and loosely directed through the slot of the mandrel, an expandible member 75 constantly urging the pin in one direction, breakable means co-acting with the carrier and mandrel for maintaining the same normally against movement under the influence of the expandible member and for normally maintaining the expandible member under compression, said gripping jaws being provided with slots in which the extremities of 80 the transverse pin are seated.

In testimony whereof I hereunto affix my signature in the presence of two witnesses.

WARREN WAGNER.

Witnesses:

I. L. TUCKER,
R. G. HEWETT.
